CLAIM

I claim the ornamental design for a closure, as shown and described.

DESCRIPTION

FIG. 1 is a top perspective view of an embodiment of the claimed design;

FIG. 2 is a bottom perspective view of FIG. 1;

FIG. 3 is a top view of FIG. 1;

FIG. 4 is a bottom view of FIG. 1;

FIG. 5 is a front view of FIG. 1, the rear view, the left side view, and the right side view being similar to the front view;

FIG. 6 is a front top perspective view of another embodiment of the claimed design;

FIG. 7 is a rear bottom perspective view of FIG. 6;

FIG. 8 is a top view of FIG. 6;

FIG. 9 is a bottom view of FIG. 6; and,

FIG. 10 is a front view of FIG. 6, the rear view, the left side view, and the right side view being similar to the front view. The broken lines are shown for the purpose of illustrating parts of the article that form no part of the claimed design.

1 Claim, 8 Drawing Sheets
